INVENTOR

Ora D. Shaw

UNITED STATES PATENT OFFICE.

ORA D. SHAW, OF EVERETT, ASSIGNOR TO SHAW & KAISER, OF BOSTON,
MASSACHUSETTS.

DESIGN FOR A CAP.

SPECIFICATION forming part of Design No. 25,235, dated March 3, 1896.

Application filed January 30, 1896. Serial No. 577,466. Term of patent 14 years.

To all whom it may concern:

Be it known that I, ORA D. SHAW, of Everett, in the county of Middlesex and State of Massachusetts, have invented and produced 5 a new and original Design for Caps, of which the following, taken in connection with the accompanying drawings, is a specification.

My design is illustrated in the accompanying drawings, in which—

10 Figure 1 is a plan or view looking directly at the top of the cap. Fig. 2 is an elevation of the same.

In general my design consists of a cap in which segmental parts A A, made comparatively plain—that is, without folds or plaits—are attached to a band B from which they project outward and then curve upward and inward so that their several points may be united at C, as shown. Alternating with the

segmental parts A A, I have underfolded and 20 semifluted connecting members D D, made of the same material as the parts A A, or, if desired, of a material showing a difference in texture, color or shade, the whole when combined producing in general the effect shown 25 in the drawings.

What I claim is—

The design for a cap as herein shown and described.

In testimony whereof I have signed my 30 name to this specification, in the presence of two subscribing witnesses, on this 24th day of January, A. D. 1896.

ORA D. SHAW.

Witnesses:

FRANK G. PARKER,
WILLIAM H. PARRY.
